24 Claims. (Cl. 315—3.6)

The present invention relates to travelling-wave tubes and more particularly to tubes of the type having crossed electric and magnetic fields.

Tubes of this kind, often referred to as M-type tubes, generally comprise two essentially parallel electrodes consisting of a delay line parallel to an electrode known as a sole, with an electric field being established between these two electrodes by applying to the delay line a positive potential with respect to the sole. The space between the delay line and the sole is additionally subjected to a magnetic field essentially perpendicular to the electric field. In the absence of the high frequency field, an electron beam directed into this space between the two electrodes will pass therethrough, parallel to the delay line and perpendicular to the crossed electric and magnetic fields. On the other hand, it is also known that in the presence of such a high frequency field, the electrons of the beam propagating inside the space between the electrodes are progressively picked up by the delay lines, i.e., little by little are absorbed by the delay lines as the beam of electrons propagates in the space along the two electrodes and the electrons impinge on the delay line structure thereby producing heat therein.

In the known tubes of this type, this beam is generally supplied by a single electron gun, a single collector being disposed at the end of the path followed by the electrons.

It is known that the output from such a tube is limited, mainly on account of the difficulties experienced with the problem of adequately cooling the delay line heated by the impact of the incoming electrons.

Under these circumstances, the only way of obtaining an output exceeding that which may normally be supplied by a given tube, is to make use of several tubes connected in parallel. However, it is known that the control of phase coincidence in a plurality of tubes of the type mentioned involves considerable difficulties. In other words, it is extremely difficult in practice to realize the exact cophasal relationship of several electron beams operating in parallel in a single tube.

It has already been proposed heretofore to dispose along a single delay line a plurality of spaced cathodes, in order to achieve a more uniform distribution of the interaction along the delay line, and thus to make better use thereof. However, such a solution will cause the beam from one cathode to pass over the adjacent cathode, so that the two beams are thereby mutually coupled, and may interfere with each other and thereby trouble the operation of the tube.

Accordingly, it is an object of the present invention to avoid all of these difficulties and disadvantages of the prior art.

It is another object of the present invention to provide a travelling wave tube capable of higher outputs than heretofore attainable with a tube of a given physical dimension.

A still further object of the present invention resides in the provision of an electron tube of the travelling wave

type adapted to be used either as amplifier or oscillator which produces larger outputs.

Still another object of the present invention is to provide such an arrangement of an electron tube of the travelling wave type in which two or more beams of electrons are propagated without any interaction with each other.

A further object of the present invention is to increase the output of an electron tube of the travelling wave type by providing two or more electron beams operative in series with respect to each other and with respect to a single delay line so as to avoid any difficulties with providing cophasal relationship of the energy produced by the interaction of the beams by the delay lines.

Still another object of the present invention resides in the construction of an electron tube of a travelling wave amplifier in which the problem involved in adequate cooling of a tube of a given size with an increase in the output thereof is solved in an advantageous manner.

These and further objects, features and advantages of the present invention will become more obvious from the following description when taken in connection with the accompanying drawing which shows, for purposes of illustration only, one embodiment in accordance with the present invention, and wherein:

Figure 1 is a cross sectional view of a tube according to the present invention, taken along line 1—1 of Figure 2, and

Figure 2 is a cross sectional view taken along line 2—2 of Figure 1.

The present invention provides a travelling-wave tube, with crossed electric and magnetic fields, comprising at least two sources of electrons located and disposed so as to radiate or emit two beams which, on the one hand are mutually uncoupled with respect to each other, and on the other hand, are each coupled with the single delay line. This uncoupling is obtained by providing between two adjacent cathodes an intermediate collector carried at or adjusted to the same potential as that of the delay line, preferably also flush with the sole in such a manner that the propagation of the wave in the delay line is not interfered with thereby.

Referring now more particularly to Figures 1 and 2 wherein like reference numerals are used in the various views to designate like parts, the tube illustrated therein

45 is a backward travelling-wave oscillator, of circular structure, known as an M-type "Carcinotron" tube. The tube comprises an evacuated cylindrical envelope 1, containing two electrodes consisting of a delay line 2 coaxial with the envelope 1 onto which it is secured, and of a circular sole 3 supported by insulating pins or sleeves 4. The delay line 2 which may be of any suitable construction is coupled at one end thereof to an output 5, and the opposite end thereof is coated with an attenuating

55 material 6 of suitable choice. A voltage source 7 with a plurality of adjustable taps supplies the necessary voltages, one of the taps, by means of connection 22 producing a radially directed electric field between electrodes 2 and 3, electrode 2 being grounded, as is also envelope 1 and the positive side of voltage source 7.

60 Furthermore, the polar pieces 8 (Figure 2) of any suitable magnet establish a magnetic field, directed along the axis of the tube. It is to be noted that the tube structure so far described above is well known per se.

According to the present invention, the tube illustrated herein includes a first electron gun 9 and a first collector 10. Gun 9 is of a well known conventional type and is disposed, as is known with the "Carcinotron" tubes, at the end of the delay lines 2, adjacent output 5. The electron gun 9 includes a cathode 16, located in a slot or

70 recess provided in the focusing plate 15, and a focusing plate 17, both plates being substantially parallel to the

general direction of propagation of the beam between line 2 and sole 3. The inner space 18 of the electron gun 9 thus constitutes essentially an extension of the space bounded by delay line 2 and sole 3. Plate 17 is biased by connection 23 and plate 15 by connection 24.

Collector 10 is secured between the walls of envelope 1, inside a slot or recess provided in sole 3, and is brought to or placed at the potential of delay line 2 by suitable connections therewith (not shown). It is placed flush with sole 3 so as not to trouble or disturb the propagation of the high frequency wave in the delay line 2. Eventually the collector 10 may also be surface-treated by any known means, so as to avoid any secondary emission therefrom.

The tube according to the present invention additionally includes a second electron gun 11 and a second collector 12. Gun 11 is located directly behind collector 10 in the direction of propagation of the electron beam, and is identical with gun 9, the electrodes 15', 16', 17', 18' thereof corresponding operatively to electrodes 15, 16, 17, 18 of gun 9. The inner space of electron gun 11, however, is slanted or inclined with respect to the mean path of the electrodes, in order to take into account the disturbing effect of collector 10 on the electric field and thereby essentially compensate for the same. The various electrodes of electron gun 11 are at the same potential as those of electron gun 9, cathode 16' of gun 11, however, being provided with a bias connection 19 independent from connection 20 of cathode 16 of gun 9, so that these two cathodes 16' and 16 might be adjusted to different potentials, if so desired.

Operation

The tube in accordance with the present invention operates as follows: beam 25 emitted from gun 9 propagates through the space between electrodes 2 and 3, across the crossed electric and magnetic fields, and then through the region of collector 10 where no electric field exists due to the same potential which is applied to both the delay line 2 and collector 10. The electrons which have not been collected or absorbed by the delay line 2 during the propagation along the delay line 2 are then deflected by the magnetic field toward this collector 10, so that beam 25 is entirely captured and removed before ever reaching gun 11.

Beam 26, emitted by gun 11, propagates under the same conditions along that portion of the delay line 2 positioned beyond collector 10, and the electrons thus emitted which have not been picked up by that portion of the delay line 2 in the course of travel thereof, are then collected, at the end of the path, by a collector 12 of known type, which is formed integral with envelope 1.

As confirmed by experience, by tilting gun 11 as described, a correct propagation of the second beam 26 is assured inside the space between electrodes 2 and 3, in spite of the disturbance in the electric field caused by collector 10.

It is to be understood that the present invention is not limited to the specific embodiment described herein given only by way of example, but is capable of many changes and modifications within the spirit of the present invention and I intend to cover all such changes and modifications as encompassed by the appended claims. Thus, for example, the present invention is not limited to the use of only two beams but may be used with more than two beams, whereby more than two beams are operatively associated with the same single delay line, the beams being operatively associated in series with respect to each other along different portions of the delay line. Moreover, the invention is not limited to the particular tube illustrated herein, but is suitable for use with any tube having crossed electric and magnetic fields whether circular or rectilinear, or whether oscillators or amplifiers. If tubes in accordance with the present invention are to be used as amplifiers, then the coupling

designated by reference numeral 5 in Figure 1 is used as input while an output coupling is provided serving as output coupling which may be constructed similar to the coupling 5 and which is located at the end of the delay line opposite to that of the coupling 5. If used as amplifier, the attenuating means 6 may be dispensed with.

Moreover, the present application is not limited to the particular showing of the attenuating means 6 but may use any other suitable external attenuating means. For example, if the tube is to be used as oscillator then the coupling normally used in connection with operation thereof as amplifier which is located at the end thereof opposite to that of the coupling 5 may be connected with an external attenuating means in which all energy flowing in the direction of travel of the electron beams 25 and 26 is dissipated.

We claim:

1. In an electron tube of the travelling wave type, the combination comprising two electrodes defining therebetween a space, one of said electrodes being a delay line having mutually uncoupled ends, and means for propagating two separate beams of electrons in said space in coupled relationship with said delay line including means to prevent interaction between said two beams.
2. In an electron tube the combination according to claim 1 wherein said last-mentioned means includes a collector at the same potential as said delay line.
3. In an electron tube the combination according to claim 2 wherein said means for propagating beams of electrons includes two electron guns, one of said guns being located behind said collector in the direction of travel of the electron beams.
4. In an electron tube the combination according to claim 3 wherein said one electron gun is inclined with respect to the direction of mean travel of said electrons.
5. In an electron tube of the travelling wave type, the combination comprising two electrodes defining therebetween a space, one of said electrodes being a delay line having mutually uncoupled ends, and means for propagating two separate beams of electrons seriatim in said space in coupled relationship with said delay line including means for decoupling said two beams.
6. In an electron tube the combination according to claim 5 wherein said delay line consists of a single delay line and wherein said means for propagating two separate beams of electrons includes two separate electron guns, and wherein one of said guns is inclined with respect to the average path of travel of said beams.
7. In an electron tube the combination according to claim 6 wherein one of said two guns is located near one end of said delay line and the other of said guns is located at a point intermediate the two ends thereof.
8. In an electron tube the combination according to claim 1 further comprising at least one coupling means for transferring energy from said delay line to an external load.
9. In an electron tube the combination according to claim 7 wherein said tube is an amplifier and is provided with two coupling means located near the two ends of said delay line.
10. In an electron tube the combination according to claim 7 wherein said electron tube is an oscillator and is provided with one coupling means near one end of said delay line and with attenuating means operatively connected with the other end of said delay line.
11. In an electron tube of the travelling wave type the combination according to claim 10 wherein said attenuating means is applied directly to said delay line.
12. In a travelling wave tube having a delay line and a non-delaysing electrode parallel thereto, said delay line and said electrode defining a space therebetween, means for generating a transverse electric field between said line and said electrode, means for generating a transverse magnetic field having lines of force crossing the electric field

lines of force, at least two electron guns positioned at different points with respect to said delay line for emitting beams propagating in said space in coupled relationship with said line, and means for decoupling said two beams.

13. In a travelling wave tube the combination according to claim 12 wherein said decoupling means includes a collector electrode located near one of said points, said collector electrode being insulated from said non-delaying electrode and being at the same potential as said delay line, said collector electrode being adapted to collect one of said electron beams.

14. In a travelling wave tube the combination according to claim 13 wherein said collector electrode is provided with an electron collecting surface flush with said non-delaying electrode and is positioned in a slot provided in said non-delaying electrode.

15. In a travelling wave tube the combination according to claim 12 wherein one of said guns is positioned in tilted relationship with respect to said delay line and non-delaying electrode.

16. A travelling wave tube of the type having crossed fields comprising, within an evacuated envelope, an anode shaped as a delay line, a member having a conductive surface parallel to said anode and bounding therewith an electron and wave interaction space, and a chain of non-overlapping systems each of which includes a source of an electron beam propagating in said space and a collector electrode at substantially the same potential as said anode and adapted to absorb substantially all the electrons of the beam, the collector of one system being located close to and preceding the electron beam source of the following system, whereby non-overlapping beams, in serial relationship with each other, are caused to propagate in the same direction in said interaction space, substantially the whole space being traversed by electrons of one beam, while each beam traverses a different portion of said space.

17. A travelling wave tube comprising, within an evacuated envelope, an anode shaped as a delay line, a negative electrode parallel to said anode and bounding therewith an electron and wave interaction space, said space being traversed by electrostatic field lines of force between said anode and negative electrode, and a chain of non-overlapping systems each of which includes a source of an electron beam propagating in said space and a collector electrode having an electron-collecting surface at essentially the same potential as said anode and adapted to absorb substantially all the electrons of the beam, the collector of one system being located within a slot provided in and electrically insulated from said negative electrode close to and preceding the electron beam source of the following system, the electron collecting surfaces of all the collectors disposed in said slots being flush with said negative electrode, whereby non-overlapping beams, in serial relationship with each other, are caused to propagate in the same direction in said interaction space, so that substantially the whole space is traversed by electrons of one beam and each beam traverses a different portion of said space, a source of magnetic field being provided to generate magnetic field lines of force through said space substantially perpendicular to said electrostatic field lines of force.

18. A traveling wave tube as claimed in claim 17 wherein at least some of the electrodes are conductor electrodes, and further comprising means for raising all the conductor electrodes to substantially the same potential as said anode.

19. In an electron tube of the travelling wave type, the combination comprising two electrodes defining therebetween a space, one of said electrodes being a delay line having mutually uncoupled ends, and means for propagat-

ing two separate beams of electrons in said space in essentially non-overlapping coupled relationship with said delay line.

5 20. In an electron tube of the travelling wave type, the combination comprising two electrodes defining therebetween a space, one of said electrodes being a delay line having mutually uncoupled ends, and means for propagating two separate beams of electrons in said space in essentially non-overlapping coupled relationship with said delay line, including means to prevent interaction between said two beams.

15 21. A travelling wave tube of the type having crossed fields including an anode shaped as a delay line, a negative electrode having a conductive surface essentially parallel to said anode and bounding therewith an electron and wave interaction space having two ends, an extreme electron gun and an extreme collector electrode located at said two ends respectively, at least one intermediate electron gun and collector electrode alternately located near intermediate points of said space so as to divide said space into adjacent portions each having an electron gun at one end and a collector electrode at the other end, each intermediate collector being located close to the next electron gun.

20 22. A travelling wave tube of the type having crossed fields including an anode shaped as a delay line, a negative electrode having a conductive surface essentially parallel to said anode and bounding therewith an electron and wave interaction space having two ends, an extreme electron gun and an extreme collector electrode located at said two ends respectively, at least one intermediate electron gun and collector electrode alternately located near intermediate points of said space so as to divide said space into adjacent portions each having an electron gun near one end and a collector near the other end, each intermediate collector being located close to the next electron gun, and means for bringing all the collector electrodes to the same potential as said delay line to thereby produce therebetween electrically fieldless spaces for stopping therein the propagation of electrons and assuring absorption thereof in the collectors, whereby non-overlapping beams, in serial relationship with each other, are caused to propagate in the same direction in said interaction space.

25 23. In an electron tube of the travelling wave type having an interaction space for propagating electrons therein under the action of mutually crossed magnetic and electric fields, the combination comprising two electrode means defining therebetween said interaction space, and cathode means within said tube for emitting electrons adapted to propagate as separate beams of electrons in said interaction space in mutually uncoupled relationship with one another and in coupled relationship with said delay line electrode means.

28 24. In an electron tube of the travelling wave type in which electrons are propagated in an interaction space under the influence of mutually crossed magnetic and electric fields, comprising a plurality of electrode means defining therebetween said interaction space, one of said electrode means being a delay line, and means within said tube including separate cathode means for propagating a plurality of beams of electrons in said interaction space in coupled relationship with said delay line electrode means and in mutually uncoupled relationship with respect to one another.
